[57] CLAIM

The ornamental design for a removable boarding handle for boats, as shown and described.

DESCRIPTION

FIG. 1 is an exploded front elevational view of a removable boarding handle for boats showing our new design; FIG. 2 is a front elevational view thereof;

FIG. 3 is a side elevational view thereof, the opposite side elevational view being a mirror image of that shown;

FIG. 4 is a rear elevational view thereof;

FIG. 5 is a top plan view thereof;

FIG. 6 is a bottom plan view thereof;

FIG. 7 is an exploded front elevational view of a second embodiment of the removable boarding handle for boats;

FIG. 8 is a front elevational view of the assembled boarding handle of FIG. 7;

FIG. 9 is a side elevational view of FIG. 8, the opposite side elevational view being a mirror image of that shown;

FIG. 10 is a rear elevational view of FIG. 8;

FIG. 11 is a top plan view of FIG. 8; and,

FIG. 12 is a bottom plan view of FIG. 8.

The broken lines shown in FIGS. 1, 2, 3 and 4 are illustrative purposes only and form no part of the claimed design.
